(57) **CLAIM**

I claim the ornamental design for a faucet, as shown and described.

DESCRIPTION

FIG. 1 is a perspective view of a faucet showing my new design;

FIG. 2 is a front side view of the faucet as shown in FIG. 1; FIG. 3 is a back-side view of the faucet as shown in FIG. 1; FIG. 4 is a top view of the faucet as shown in FIG. 1; FIG. 5 is a bottom view of the faucet as shown in FIG. 1; FIG. 6 is a left-side view of the faucet as shown in FIG. 1; and,

FIG. 7 is a right-side view of the faucet as shown in FIG. 1. The broken lines are only for environmental purposes and form no part of the claimed design.
